UNITED STATES PATENT OFFICE.

FREDERICK A. OSBORN, OF SAN FRANCISCO, CALIFORNIA.

DESIGN FOR A BADGE.

SPECIFICATION forming part of Design No. 22,985, dated December 26, 1893.

Application filed October 24, 1893. Serial No. 489,053. Term of patent 14 years.

To all whom it may concern:

Be it known that I, FREDERICK A. OSBORN, a citizen of the United States, residing in the city and county of San Francisco and State of California, have invented and produced a new and original Design for a Badge, of which the following is a specification, reference being had to the accompanying drawing, forming part thereof.

- 10 The leading feature of my design consists of a four-pointed shield having its arms or members extending in perpendicular and horizontal directions and of equal length substantially like the arms of a Greek cross.
- 15 The outlines of these arms are on curved lines with alternating inner and outer curves, and the ends of the four arms have Gothic terminals substantially like two ogee curves 1—1 meeting together in an acute point 2.
- 20 The contour of the arms from the Gothic ends follows alternate inner and outer curves, and where they meet at the junction of one arm with another the contour follows a semi-circle or deep re-entering curve. All these curves

run gracefully and smoothly into one another 25 all around the outline of the figure. The field within this outline is divided by two curved lines or narrow bands 4—4— into a central space —5— that extends horizontally across from one side-arm to the other, and an 30 upper space —6— above and a lower space —7— on the lower arm of the cross. The upper space or field —6— contains a picture of a horse fallen under a load with the driver in the act of beating the animal and a looker on 35 interfering to protect the animal. The remaining spaces are for letters and figures which the badge is intended to display.

Having thus described my said invention, what I claim as new, and desire to secure by 40 Letters Patent, is—

The design for a badge as herein shown and described.

FREDERICK A. OSBORN.
